UNITED STATES PATENT OFFICE.

EDWARD H. PHIPPS, OF CINCINNATI, OHIO.

HINGE STRUCTURE.

1,417,563.

Specification of Letters Patent. Patented May 30, 1922.

Application filed September 25, 1919. Serial No. 326,166.

To all whom it may concern:

Be it known that I, EDWARD H. PHIPPS, a citizen of the United States, residing at Cincinnati, in the county of Hamilton and 5 State of Ohio, have invented certain new and useful Improvements in Hinge Structures, of which the following is a specification, reference being had to the accompanying drawings.

10 This invention relates to certain improvements in receptacles and has relation more particularly to a device of this general character especially designed and adapted for use in connection with reels for moving 15 picture films, and it is an object of the invention to provide a novel and improved device of this general character which in its construction comprises a small number of parts which, when assembled, afford a 20 structure possessing strength whereby the transporting of the same effectively protects the contents of the receptacle.

A still further object of the invention is to provide a device of this general character 25 including hingedly connected sections, together with novel and improved means whereby the sections may be locked in closed position.

The invention consists in the details of 30 construction and in the combination and arrangement of the several parts of my improved receptacle whereby certain important advantages are attained and the device rendered simpler, less expensive and otherwise more convenient and advantageous for use, as will be hereinafter more fully set forth.

The novel features of my invention will hereinafter be definitely claimed.

40 In order that my invention may be the better understood, I will now proceed to describe the same with reference to the accompanying drawings, wherein:

Figure 1 is a view in end elevation of a 45 receptacle constructed in accordance with an embodiment of my invention with the sections closed;

Figure 2 is a view in end elevation of the 50 receptacle as herein embodied, with the sections open and reels applied within each of the sections;

Figure 3 is an enlarged vertical sectional 55 view taken through the device, as illustrated in Figure 1;

Figure 4 is an enlarged fragmentary view in elevation illustrating the means for

pivots connecting the sections of the receptacle, and which means also serve as a handle for carrying the receptacle;

Figure 5 is a fragmentary view in elevation showing the means for holding the sections in closed position, a coacting lock being indicated by dotted lines, and

Figure 6 is a view in elevation of the members for holding the sections of the receptacle closed.

As herein embodied my improved receptacle comprises two sections A and B of substantially duplicate construction, and each semi-cylindrical, so that, when the sections are in closed relation, the receptacle will be cylindrical in form, and which configuration results in the same being particularly adapted for use in connection with reels for moving picture films.

Each of the sections A and B comprises a sheet 1, preferably of metal, and bended or flexed into desired form, and coacting with the opposite ends thereof are the end plates 2, also preferably of metal, and semi-circular in form. The rounded marginal portion of each of the plates is provided with the inwardly directed and substantially perpendicularly related flanges 3, which are preferably spot welded to the plate 1. 85 Suitably applied to the outer faces of the plates 1 and 2 are the laminations 4, preferably fibre board, and which laminations serve as an effective protection for the plates 1 and 2. The inner faces of the plates 1 90 and 2 also have suitably secured thereto the laminations 4^a, preferably of fibre board, to further protect such plates, and, as is particularly illustrated in Figures 3 and 7, it is to be noted that said laminations 4^a terminate a slight distance inwardly of the straight edges of the plates 1 and 2 for a purpose to be hereinafter more particularly referred to.

The straight edges of the plate 1 are provided with the rolled extensions 5, which afford sleeves or knuckles, and the sleeves or knuckles of one section are adapted to mesh or interlock with the sleeves or knuckles of the second section, as is clearly illustrated in Figures 4 and 5. Coacting with the sleeves or knuckles 5 at adjacent edges of the plate 1 is a pivotal member P. The member P initially comprises two sections including straight portions 6, which extend through 105 Figures 4 and 5. Coacting with the sleeves or knuckles 5 at adjacent edges of the plate 1 is a pivotal member P. The member P initially comprises two sections including straight portions 6, which extend through 110 the meshing or interlocking sleeves or knuckles 5, and serve as pintles for hingedly

connecting the sections A and B. The outer ends of the straight portions 6 are continued by the laterally and inwardly inclined portions 7, which are also continued by the inwardly directed straight portions 8 arranged substantially in parallelism with the portions 6. After the portions 6 have been properly engaged through the knuckles or sleeves 5 the inner extremities of the portions 8 are welded or otherwise connected, as at a so that the member P is effectively maintained in applied position, and accidental complete separation of the sections A and B substantially eliminated. By this construction of the member P, said member affords a loop or hand grasp whereby the receptacle may be readily and conveniently carried by a person.

The knuckles or sleeves 5 at the opposite sides of the sections A and B interlock or mesh when the sections A and B are closed one with respect to the other, and coacting with said sleeves or knuckles 5 are the pintles H, each of the holding members H comprising a straight portion 9 adapted to be inserted through certain of these knuckles or sleeves 5, and said portion 9 is continued by a returned portion 10 substantially in parallelism with the portion 9 but slightly spaced therefrom. The portion 10 terminates in an eye 11. The portions 9 of the pintles H are inserted through the knuckles or sleeves 5 at opposite ends of the receptacles, and the same are moved inwardly until the members 11 are brought into register. The shackle of a lock of desired type, or other means, is then inserted through the eyes, whereby the sections A and B are effectively locked in closed relation.

As is illustrated in Figure 2, it is to be noted that the portions A of the member P are spaced sufficiently from the portions 6 so that the member P will offer no obstruction to the opening or separating movement of the sec-

tions A and B, and so that said sections may be brought substantially into alignment in order to permit the application or removal of the reels R of one of the open sections independently of the other.

From the foregoing description, it is thought to be obvious that a receptacle constructed in accordance with my invention is particularly well adapted for use by reason of the convenience and facility with which it may be assembled and operated and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A device of the class described comprising two sections, similar marginal portions of the sections being provided with knuckles adapted to intermesh when the sections are closed one with respect to the other, pintles insertable through the knuckles from opposite sides, and means for locking said pintles in working position.

2. A device of the class described comprising two hingedly connected sections, similar marginal portions of the sections being provided with knuckles adapted to intermesh when the sections are closed one with respect to the other, pintles insertable through the knuckles from opposite sides, the outer end portions of the pintles being returned and terminating in eyes, said eyes substantially registering when the pintles are in applied position, and means coacting with the eyes for locking the pintles in working position.

In testimony whereof I hereunto affix my signature.

EDWARD H. PHIPPS.
